UNITED STATES PATENT OFFICE.

WILLIAM F. SINGER, OF CARTHAGE, ASSIGNOR OF ONE-HALF TO GILBERT L. HAVILAND, OF SYRACUSE, NEW YORK.

THERMOSTAT.

SPECIFICATION forming part of Letters Patent No. 450,260, dated April 14, 1891.

Application filed July 29, 1890. Serial No. 360,314. (No model.)

To all whom it may concern:

Be it known that I, WILLIAM F. SINGER, a citizen of the United States, residing at Carthage, in the county of Jefferson and State of New York, have invented certain new and useful improvements in Thermostats; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in thermostats; and it has for its object to generally improve upon the construction and to render more efficient in operation this class of appliances.

20 The more immediate object of the present invention is to provide a thermostat which is adapted especially for use in connection with closed-circuit fire-alarm systems, the construction of the instrument being such as to adapt 25 it to automatically break the circuit when the temperature has reached such a point as may be necessary to fuse the disk-retaining devices, as will hereinafter appear, and also to afterward restore the current or circuit, thus

30 indicating that the operation of the instrument was due to a genuine fire in contradistinction to the alarm which would be given in case of accident or through malicious tampering with the instrument, either of which 35 causes would serve to operate the thermostat and cause a break in the circuit, but would not again restore it to its normal closed condition.

To these ends and to such others as the invention may pertain, the same consists in the peculiar construction and in the novel combination, arrangement, and adaptation of parts, all as more fully hereinafter described, shown in the accompanying drawings, and 45 then specifically defined in the appended claims.

The invention is clearly illustrated in the accompanying drawings, which, with the letters of reference marked thereon, form a part 50 of this specification, like letters of reference

indicating like parts throughout the several views, in which—

Figure 1 is a bottom plan view of a thermostat constructed in accordance with my invention. Fig. 2 is a central vertical section 55 of the same, showing the parts as they appear when in a normal condition. Fig. 3 is a top plan view. Fig. 4 is a central vertical section of the instrument, showing the parts as they appear after the instrument has been 60 acted upon by a rise in temperature. Fig. 5 is a like view showing the position of the parts after the circuit has been automatically restored.

Reference now being had to the details of 65 the drawings by letter, A represents the thermostat, which is made of sheet metal and is of the usual form, being secured to the ceiling of the apartment by screws passed through openings a in the ears B, which ears extend 70 beyond the periphery of the top plate C. The blocks of hard rubber D and D' are secured to the inner walls of the case upon opposite sides of the same, the block D being upon a higher plane than the block D', as shown. 75

E and E' are strips of spring metal, which are secured to the blocks D and D', the opposite or free ends of the strips being provided with contact-points E³ and E'³.

A supplemental bottom F, composed of the two sections F' and F'', is supported upon the inwardly-extended projection G, and at the center of this bottom a fusible plug c is inserted in a screw-threaded opening provided for its reception. A post H, having its lower end 85 screw-threaded, is inserted within the screw-threaded opening c' in the bottom F, the upper end of this post bearing against the lower face of the spring E, forcing the free end of the said spring upward slightly, as shown in 90 Fig. 2 of the drawings. The bottom I is of sheet metal, and is preferably convex upon its exterior surface. To this bottom is secured the lower end of the post d, the upper end of the said post having a bearing against 95 the lower face of the spring-arm E'. The bottom I is secured in place by the fusible plugs I', which are inserted within the screw-threaded openings provided in the lower edges of the case for their reception. The current is 100

maintained through the contact-points carried by the spring-arms E and E', the wires leading to the different poles of the battery being connected to the screws, which secure the said strips to the hard-rubber blocks D and D', as shown.

In operation an increase of temperature in the apartment sufficient to cause the fusion of the plugs G will cause the bottom to drop out, thus removing the supporting-post d from its engagement with the spring-arm E', which springs downward, separating the contact-points and breaking the circuit, the parts assuming the positions indicated in Fig. 4 of the drawings. The bottom having been thus removed, the heat is given access to the fusible plug c, which is in turn melted, allowing the sectional bottom F' and F² to drop, the section F' carrying with it the post c', and the spring-arm E is thrown downward by the elasticity of the spring material of which it is composed, thus causing the contact-points to unite, as shown in Fig. 5, and closing the circuit, this closing of the circuit serving to give notice of the fact that the action of the thermostat has been due to an actual fire.

Having thus described my invention, what I claim to be new, and desire to secure by Letters Patent, is—

30 1. A thermostat having contact-points carried by spring-arms, two independent bottoms, each bottom being held normally in po-

sition by fusible plugs, and supports between the respective bottoms and the spring-arms carrying the contact-points, whereby an electric circuit will be broken and afterward restored by the displacement of the respective bottoms occasioned by the fusing of the plugs, substantially as described. 35

2. A thermostat having two independent bottoms each held normally in position by fusible plugs, spring-arms carrying contact-points, through which the circuit is maintained, and posts or supports for said arms connected with the bottoms, substantially as 40 45 shown and described, and for the purpose specified.

3. The combination, with the case, the spring-metal arms, and the contact-points carried by said arms, of two independent bottoms normally retained in place by fusible plugs, and connections, substantially as 45 50 described, between said bottoms and the spring-metal arms, whereby the circuit through the thermostat will be automatically broken and subsequently closed by the fusing of the plugs retaining the bottoms, substantially as and for the purpose described. 55

In testimony whereof I affix my signature in presence of two witnesses.

WILLIAM F. SINGER.
